UNITED STATES PATENT OFFICE.

LOUIS WECHSLER, OF NEW YORK, N. Y.

MOP AND BRUSH HOLDER.

1,342,036.

Specification of Letters Patent.

Patented June 1, 1920.

Application filed September 5, 1919. Serial No. 321,792.

To all whom it may concern:

Be it known that I, LOUIS WECHSLER, a citizen of the United States, and a resident of the city of New York, borough of Manhattan, in the county and State of New York, have invented a new and Improved Mop and Brush Holder, of which the following is a full, clear, and exact description.

10 This invention relates to scrubbing and brushing apparatus and has particular reference to a device so designed as to hold either a mop head or a scrubbing brush.

Among the objects of the invention therefore is to so construct a mop stick and attachment means at the end thereof as to accommodate the device for holding and manipulating any one of several different types of cleansing devices.

20 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate 30 the same parts in the several views, and in which—

Figure 1 is a plan view of my improvement shown as holding a scrubbing brush.

Fig. 2 is a side elevation of the same.

35 Fig. 3 is a plan view of the device set to hold a mop; and

Fig. 4 is a detail perspective view of the lower jaw member of the head.

Referring now more specifically to the drawings for a description of the mechanism and its mode of operation I show at 10 a mop stick or handle upon the reduced end 11 of which is fitted a head 12 in rigid position, the same comprising a pair of spaced jaw members 13 and 14 forming a channel 15 in which a bail 16 operates under the force of an expansion spring 17 for the purpose of holding a mop 18 in position. The spring is located around the 45 reduced end portion 11 of the stick and bears expansively at its ends against a collar 19 and said head 12. The collar is movable longitudinally of the stick and is limited in such movement by means of a shoulder 20 at the upper end of the reduced 50 portion of the stick. The collar has trun-

nions 19' projecting radially from opposite sides thereof and upon which is journaled a lever 21 to which the bail is attached at 22. The collar constitutes the fulcrum for 60 the lever and the spring as a resilient base or cushion therefor providing for a suitable grip upon the mop that is introduced between the lower cross-bar portion of the bail and the bottom of the channel 15 when 65 the lever is swung to its open position around the trunnions 19'.

As indicated in Fig. 4 the lower jaw member 14 of the head is cut-away at 14^a providing ample clearance for the location 70 and operation of the mop 18, but at the ends of this cut-away there are left a pair of prongs 14^b extending parallel to the flange portion 13^a of the upper jaw 13, but having their points directed toward said 75 flange 13^a.

Coöperating with the upper jaw 13 is a clip 23 formed preferably of a substantial piece of strap metal and having a longitudinal slot 24 through which a clamping 80 bolt 25 projects. The bolt is carried by the socket portion 26 of the mop head and a winged nut 27, or its equivalent, coöperates with the bolt on the outer surface of the clip to lock the clip in either of two pre-determined positions. One of these positions is as shown in Figs. 1 and 2 in which the middle portion of the clip is embraced by a pair of spaced hooks 28 formed on or secured to the lip 13^a with the longer 90 axis of the clip lying parallel to the axis of the handle or stick 10. The clip when locked in this position by means of the nut 27 is rigid with the handle, and the forward or lower end formed in the shape 95 of a hook 29 is adapted to embrace the side or edge of the brush back 30 while the rear edge of the same is engaged within the channel 15 and securely held by the hooks 14^b. Since the clip 23 cannot swing laterally it follows that the brush is securely held from movement in any direction with respect to the mop stick.

The side edges of the clip are provided with notches 31 which are adapted to register with the hooks 28 when the nut is loosened and it is desired to swing the clip around so as to nest in idle position just above and parallel to the lip 13^a as shown in Fig. 3. It follows therefore that the 110 clip will always be retained by the mop head and will always be in position for

use as required for the purpose of holding the brush. The brush holding device is very simple and reliable, and yet cheap of manufacture and easy to manipulate and adds but little to the weight and nothing to the inconvenience in use with respect to the mop.

I claim:

In a device of the class set forth, the combination with a mop head and means co-operating therewith to hold the mop, of

means to hold a scrubbing brush in connection with the mop head, said means comprising a pair of spaced hooks on the lower portion of the mop head for coöperation with one edge of the brush back, and a clip having adjustable connection with the upper part of the head and having a hook projecting forward and downward around the opposite edge of the brush back. 15

LOUIS WECHSLER.
